UNITED STATES PATENT OFFICE.

FRANK H. WHITE, OF PHILADELPHIA, PENNSYLVANIA.

TRAVELING-CASE.

SPECIFICATION forming part of Letters Patent No. 739,627, dated September 22, 1903.

Application filed February 3, 1903. Serial No. 141,700. (No model.)

To all whom it may concern:

Be it known that I, FRANK H. WHITE, a citizen of the United States, residing at Philadelphia, county of Philadelphia, and State of Pennsylvania, have invented a new and useful Improvement in Traveling-Cases, of which the following is a full, clear, and exact description, reference being had to the accompanying drawings, which form a part of this specification.

My invention relates to that class of traveling-cases known as "dress-suit" cases, and has for its object to provide a suitable compartment for containing shirts, shirt-waists, cuffs, and, if desired, collars. Much difficulty is experienced by travelers in keeping shirts or shirt-waists separate from the other contents of the case and in preventing them from soiling by coming into contact therewith. It is also troublesome to remove and replace them whenever access to the case is desired. Sometimes they are strapped in, but they are liable to slip out unless they occupy practically the entire superficial area of the case, and the straps must be unfastened when it is desired to remove a shirt and again fastened.

By my invention I provide means whereby the shirts may be quickly packed or unpacked whether the case is otherwise empty or filled, whereby they are kept separate from the other contents and prevented from soiling and whereby a space within the case that would otherwise be wasted is utilized for the shirts and the entire body of the case reserved for the other contents.

In the drawings, Figure 1 is a perspective view of a dress-suit case with my invention applied. Fig. 2 is a view of blank in an extended position. Fig. 3 is a partial section taken on line 3 3, Fig. 1.

A represents the body of the case and B the lid, having the usual downturned flanges b.

C is a flat thin plate of an area equal to the inner dimensions of the lid and may be made of pasteboard or similar material.

D is a fabric lining of an area equal to the area of the plate C and secured thereto along its edges. A thin layer of padding is confined between the plate and its lining.

E is a blank of satin, silk, or other material and may be formed initially of the shape illustrated in Fig. 2. As so shaped, the one

side of the blank is straight and the other side has two short shallow concavities and two relatively long and deep concavities. 55 This blank is bent in the direction of the plane of its extension, so that the long flat edge e thereof lies on the outside and the indented or irregular edge e' on the inside and the short edges e² e² secured together except 60 for a short distance adjacent to the edge e'. The blank is also bent slightly along the edge e' to form a hem e³, which is stitched to the body of the blank. An elastic band F is inserted between the body of the blank and the 65 hem and passed entirely around the same, being confined in place by the stitching. The ends of the elastic are then secured together, forming, in effect, an elastic band. The blank is now laid down flat upon the lined plate C 70 D and the overlapping edges bent under the plate and secured thereto by glue or otherwise. The plate C D is now inserted into the lid and secured therein in any suitable manner. By reason of the width of the blank being less than the distance from the center to the outer edge of the lid the central portion inclosed by the band F will not close up, 75 but will remain open and form a small central orifice. When the blank is bent, as described, the two short shallow concavities are brought opposite each other, and the two long deep concavities are brought opposite each other, thus causing the orifice to be elongated into an approximately oval shape, 85 as shown. Thus is formed in the lid of the box a compartment having a fabric lining in the bottom and a fabric cover provided with a small central orifice. The elastic band draws the fabric tightly toward the center of 90 the lid and maintains the orifice normally small; but as the original length of the inner edge e' is as great as the original length of the outer edge e and the fabric around the orifice consequently very much gathered or 95 puckered the orifice can readily be distended by hand to the extent necessary to permit the insertion of a shirt, while under the action of the elastic it immediately contracts to its normal size when the hand is withdrawn. Thus 100 shirts may be kept entirely separate from the other contents of the case. They can be inserted or removed without disturbing the other contents. They will not soil, as they

are effectually protected by the elastic cover, and the space within the lid, which would otherwise be unoccupied or only partially occupied, is utilized. Collars and cuffs may 5 also be inserted within the compartment, if desired.

Straps G G' may be secured to opposite sides of the lid and extend crosswise of the compartment and be fastened together by 10 means of suitable fastening members g g'.

Having now fully described my invention, what I claim, and desire to protect by Letters Patent, is—

1. In a dress-suit case, an annular cover secured to the lid and formed of a long narrow blank having one edge indented or irregular and bent in the direction of the plane of its extension with the indented or irregular edge on the inside and the abutting ends secured 15 together, combined with an elastic band engaging the cover contiguous to its indented inner edge and of a normal length substantially less than the length of said inner edge, substantially as described.
2. In a dress-suit case, an annular cover secured to the end and formed of a long narrow blank bent in the direction of the plane of its extension and having its abutting ends secured together whereby the inner edge of 20 the cover is gathered or puckered, combined with an elastic band engaging the portion of the cover contiguous to the orifice it incloses and of a normal length substantially less than the length of the inner edge of the cover 25 whereby said orifice is normally contracted.
3. In a dress-suit case, the combination,

with the lid, of an annular cover having its outer edge secured thereto and its inner edge formed with two opposite short shallow concavities and two opposite relatively long 40 deep concavities, the inner edge of the cover being flexible, whereby there is formed a normally small elongated orifice capable of being expanded to permit of the insertion or removal of a shirt, substantially as described. 45

4. In a dress-suit case, the combination, with the lid, of a plate secured to the bottom of the lid, an annular cover overlapping said plate and secured to its edges, the outer edge of the cover being substantially equal in length to the inner edge, thereby causing the inner portion of the cover adjacent to the central orifice to gather or pucker, substantially as described.

5. In a dress-suit case, the combination, 55 with the lid, of a plate secured to the bottom of the lid, an annular cover overlapping said plate and secured to its edges, the outer edge of the cover being substantially equal in length to the inner edge, thereby causing the inner 60 portion of the cover adjacent to the central orifice to gather or pucker, and an elastic band engaging said cover near its inner edge and normally contracting said orifice, substantially as described. 65

In testimony of which invention I have hereunto set my hand, at Philadelphia, on this 29th day of January, 1903.

FRANK H. WHITIE.
